DESIGN FOR A HOLDER FOR MAGAZINES, NEWSPAPERS, OR THE LIKE

Morris Katcher, New York, N. Y.

Application March 14, 1940, Serial No. 90,919

Term of patent 7 years

To all whom it may concern:

Be it known that I, Morris Katcher, a citizen of the United States, residing at New York, in the county of Queens and State of New York, have invented a new, original, and ornamental Design for a Holder for Magazines, Newspapers, or the like, of which the following is a specification, reference being had to the accompanying drawing, forming part thereof.

Fig. 1 is a perspective view of a holder, for magazines, newspapers or the like, showing my new design;

Fig. 2 is a top plan view; and

Fig. 3 is a side elevational view thereof, taken from a point looking to the left of Fig. 2.

I claim:

The ornamental design for a holder for magazines, newspapers or the like, as shown.

MORRIS KATCHER.
